UNITED STATES PATENT OFFICE.

JAMES C. OLIVER, OF LOUISVILLE, KENTUCKY.

BUGGY-TOP.

SPECIFICATION forming part of Letters Patent No. 296,045, dated April 1, 1884.

Application filed January 16, 1884. (No model.)

To all whom it may concern:

Be it known that I, JAMES C. OLIVER, a citizen of the United States, residing at Louisville, in the county of Jefferson and State of Kentucky, have invented certain new and useful Improvements in Buggy-Tops, of which the following is a specification, reference being had therein to the accompanying drawings.

10 My invention relates to certain new and useful improvements in buggy-tops; and it consists in arranging said top in such a manner that the front may be extended at will without moving the upright bows, and providing for the ingress and egress to the buggy without the interference of the upright bows; and it further consists in dispensing with two or more bows usually employed or used in an ordinary buggy-top, and using only two bows. 15 The object of my invention is to provide a buggy-top that is light and durable, constructed with only two upright bows, and yet display the same or more cover-surface to protect from storm and sun; second, to construct 20 a top that will permit the occupant to get in or out of the buggy without the inconvenience of the slanting front bow usually found in ordinary buggy-tops; third, to form a top that will fold back, that will present a neat and 25 compact appearance, that will ride with little or no wear, and present but little surface for resistance against the wind or the forward movement of the buggy. I attain these objects by means of the peculiar construction 30 and various arrangements of the parts, which will be more fully pointed out and described in the specification and claim, reference being had to the drawings accompanying this application and forming part of the same, in 35 40 which—

Figure 1 is a side elevation of my invention, showing the top extended. Fig. 2 is a side elevation, showing the front joint bent and the front bow pressed back against the rear bow. Fig. 3 is a side elevation, showing the top partly closed back of seat. Fig. 4 is a side elevation, showing the top closed back, with hood-extension folded down on front bow. 45

Similar letters refer to similar parts throughout the drawings.

Referring to the drawings, A represents my improved buggy-top, formed as hereinafter described, and with the ends of the two bows pivoted to projections on the seat B. Projections F are secured to the sides of seat B, 55 and are provided with pins formed to receive the ends of bows D E, which are formed of the usual size and height. To the front bow, extending forward, is formed the skeleton front or hood C, which is held in place by the joints 60 H and J and the cover e, said hood being formed of curved cross-slats a, a', and a'', the front cross-slat, a'', being held at right angles to the slat a by means of connecting braces a'', one end of which is attached to slat a, 65 and the opposite ends to said front curve slat, a''. Slat a' is set in front of slat a, and the ends are perforated at the points where said ends cross the ends of slat a'', which is also perforated to receive a pivot-bolt, b, on which 70 one end of joint H is pivoted, as shown in Fig. 2, said joint being formed to bend upward by means of its central joint, the opposite end of joints H being pivoted at points near the top of bow D. One end of the joints I is also 75 pivoted at the same point, and their opposite ends are pivoted at G to the back of seat B. Two joints, J, that operate the hood or extension C, are secured by their ends to slat a and bow E in such a manner, as shown in Figs. 2, 80 3, and 4, that the hood C will be extended when the joints H and J are extended, or when the joints H are bent upward in the center. When the joints H are bent upward and the joints I are bent backward, the top is closed 85 down on the seat, as shown at Fig. 3, and at the same time the hood, by means of the joints J, if desired, is folded down onto the bow E, as shown in Fig. 4. A back projecting bow or slat, b, is fitted in at right angles with bow 90 D, and is connected by its ends to the same bolt or pivot-pin that holds the ends of joints H and I, and the outer surface of the bows and extensions is covered with stays and leather or enameled cloth in the usual manner, making a cheap and durable top; also, one of great convenience to the occupant in getting in and out of the buggy; also, in affording greater protection from the weather than those that are now in general use. 95 100

Having described my invention, what I claim, and desire to secure by Letters Patent, is—

In a buggy-top, the hood provided with the extension-joints J and curved slats *a*, *a'*, and *a''*, substantially as shown, in combination with the pivoted flexible joints H and I, the pivoted bows D and E, and rear extension, *b*, the

parts being constructed substantially as shown, for the purpose set forth.

10

In testimony whereof I affix my signature in presence of two witnesses.

JAMES C. OLIVER.

Witnesses:

M. RABBETH,
HARRY JOINT.
